ATTORNEY

UNITED STATES PATENT OFFICE.

VALENTINE LAICK, OF TYRE, PENNSYLVANIA,

CUSPIDOR.

1,111,544.

Specification of Letters Patent. Patented Sept. 22, 1914.

Application filed August 5, 1913. Serial No. 783,154.

To all whom it may concern:

Be it known that I, VALENTINE LAICK, a citizen of the United States of America, residing at Tyre, in the county of Allegheny and State of Pennsylvania, have invented 5 certain new and useful Improvements in Cuspidors, of which the following is a specification, reference being had therein to the accompanying drawing.

10 This invention relates to cuspidors, and the objects of my invention, are, first, to provide a cuspidor with simple and effective means for preventing the contents thereof from being spilled when the cuspidor is 15 tilted or accidentally upset; second, to provide a cuspidor consisting of comparatively few parts that can be easily cleaned and maintained in a sanitary condition; third, to provide a cuspidor that can be advantageously used in hotels, theaters, depots and other public places where floors and carpets are liable to be injured by the upsetting of a cuspidor, and fourth, to provide a cuspidor that is simple in construction, susceptible to 25 any desired ornamentation, and highly efficient for the purposes for which it is intended.

I attain the above objects by a mechanical construction that will be hereinafter specifically described and then claimed, and reference will now be had to the drawing, wherein:—

Figure 1 is a vertical sectional view of a cuspidor in accordance with this invention, 35 and Fig. 2 is a plan of a portion of the cuspidor.

A cuspidor in accordance with this invention comprises two cylindrical sections 1 and 2, the section 1 having a flat bottom 3 provided with a central hollow conical-shaped support 4 for a detachable conical-shaped deflector 5 of less diameter than the section 1. The deflector 5 has a shell 6 that fits over the upper end of the support 4, whereby the 45 deflector can be easily removed and the section 1 thoroughly cleaned and maintained in a sanitary condition. The section 1 has the lower edges thereof provided with diametrically opposed and outwardly extending lugs 7 that are provided with seats 8. The upper edges of the section 1 have a circumferen-

tially arranged socket 9 that is U-shaped in cross section and located within said socket is a gasket 10, preferably made of rubber or other resilient material. The gasket 10 55 is U-shaped in cross section and receives the lower edges of the section 2.

The top of the section 2 is closed, as at 11 and provided with a central depending funnel-shaped mouth piece 12, the lower end of 60 which extends into a plane with the lower edges of said section. The lower or inner end of said mouth piece has an inverted conical-shaped deflector 13 that is formed integral with said mouth piece, said inverted deflector coöperating with the deflector 5 in preventing the contents of the cuspidor from entering the mouth piece 12, when the cuspidor is upset. The upper edges of the section 2, at diametrically opposed points has 65 apertured lugs 14 and extending through said lugs are tie rods 15 having heads 16 engaging in the seats 8 of the lugs 7. Nuts 17 are screwed upon the upper ends of said tie rods, whereby the sections 1 and 2 can be 70 locked together to insure a non-leakable connection between said sections and provide a receptacle for spittle and other matter. It is through the medium of the tie rods that the sections of the cuspidor can be separated and 75 thoroughly cleaned and maintained in a sanitary condition, and it is through the medium of the deflectors 13 and 5 that the contents of the cuspidor cannot be spilled should the same be accidentally upset or tilted. 85

One embodiment of the invention has been illustrated but it is to be understood that the structural elements are susceptible to such variations and modifications as fall within the scope of the appended claims. 90

What I claim is:—

1. A cuspidor comprising a cylindrical body portion formed of an upper and lower section, said lower section having its top edge provided with a socket for the reception of said upper section, each of said sections provided with a pair of apertured lugs, said lower section being closed at its bottom and said upper section open, tie bars extending through said lugs and having heads at 95 their lower ends countersunk in the lugs of said lower section, and handles mounted 100

upon said tie bars and engaging the lugs of the upper section.

2. A cuspidor comprising a body portion formed of a pair of abutting cylindrical sections, each of said sections provided with apertured lugs, tie bars extending through said lugs and having heads set in the lugs of the lower section and handles mounted

upon the upper ends of said tie bars and engaging the lugs of the upper section.

In testimony whereof I affix my signature in the presence of two witnesses.

VALENTINE LAICK.
